DESIGN FOR A GOGGLE FRAME

Joseph Brunetti, Carlstadt, N. J., assignor to
Columbia Protektosite Co., Inc., Carlstadt, N. J.,
a corporation of New Jersey

Application February 24, 1945, Serial No. 118,128

Term of patent 7 years

(Cl. D57—1)

To all whom it may concern:

Be it known that I, Joseph Brunetti, a citizen of the United States and resident of Carlstadt, in the county of Bergen and State of New Jersey, have invented a new, original, and ornamental Design for a Goggle Frame, of which the following is a specification, reference being had to the accompanying drawing, forming a part thereof, and of which Figure 1 is a front

view of a goggle frame showing my new design; Fig. 2 is a fragmentary bottom plan view thereof; Fig. 3 is a side view thereof; and Fig. 4 is an enlarged sectional view on line 4—4 of Fig. 3.

I claim:

The ornamental design for a goggle frame, substantially as shown.

JOSEPH BRUNETTI.
